UNITED STATES PATENT OFFICE.

CONRAD KAHLER, OF CHICAGO, ILLINOIS.

PAPER-FOLDING MACHINE.

SPECIFICATION forming part of Letters Patent No. 294,472, dated March 4, 1884.

Application filed April 16, 1883. (No model.)

To all whom it may concern:

Be it known that I, CONRAD KAHLER, residing at Chicago, in the county of Cook and State of Illinois, and a citizen of the United States, have invented new and useful Improvements in Paper-Folding Machines, of which the following is a full description, reference being had to the accompanying drawings, in which—

10 Figure 1 is a top or plan view; Fig. 2, a longitudinal vertical section on line x of Fig. 1. The object of this invention is to improve the construction and operation of the printing-press folder described in the application 15 filed by me in November, 1882, in stopping or detaining the advance sheet by catching and holding it at the rear edge, instead of stopping it by the leading edge, as shown in my previous application.

20 To such end the invention consists in the combination and arrangement of devices hereinafter set forth and claimed.

In the drawings, A indicates the frame-work; A', extended posts or brackets for supporting 25 one of the return-rollers for the upper tapes; B, folding-rollers; C, cam-wheel for operating the folding-blade; D, folding-blade; E, cam-wheel for operating the sheet-divider; F, cam-wheel for operating the detaining-fingers; 30 G H I J K, tape-rollers; L, cross-shaft upon which the cam-wheel is mounted; a, the upper set of tapes; b, the lower set of tapes; c, shaft of the divider; d, dividing-fingers; e, parting-roller for keeping the tapes separate; f, cross-bar located between the tapes in the rear of 35 the dividing-roller e; g, rock-shaft; g', detaining-fingers attached to the rock-shaft g; h, arm or lever by which the shaft g is rocked; i, rod connecting the arm h with the lever l; j, spring; 40 k, stop for the spring; l, pivoted lever operated by the cam-wheel F; m, friction-roller of the lever l, that presses against the periphery or rim of the cam-wheel F; n, pivoted lever operating on the side of the cam-wheel F; o, 45 posite to the lever l; o, connecting-rod; p, spring; q, roller or rod for supporting the tapes; r, a bent or V lever; s, starting-roller; t, pivot-lever operated by the cam-wheel E; u, connecting-rod; v, spring; w, arm or lever 50 for rocking the shaft c.

The frame A A' is usually made of iron, and is best made in the form shown.

The rollers B are the upper set of rollers for an ordinary folding-machine. The remaining sets or pairs are not shown, as they are to be of the ordinary construction.

The cam-wheel C and the blade D are also of the ordinary construction.

The wheels or disks E F, as shown, are so made as to give the levers l, n, and t their proper movements, and, if desired, they may be provided with cam-grooves in their faces or sides for giving these levers their proper movements.

This folder is designed to be connected 65 with a web-printing press, and it will be understood that the tapes a b are to be properly extended and supported for taking the printed sheets as they come from the press, or from the cutting-rollers thereof; and it will also be 70 understood that this folder may be arranged close to the tail of the press or at some distance from it, as the exigencies of its location or that of the press may require.

The dividing-fingers d are firmly attached 75 to the rock-shaft c, and their ends are arranged to operate near the rollers G, so as to divide and direct the advancing sheets alternately over and under the roller e and the plate or bar f. The roller e keeps the upper tapes elevated from the lower, and aids these tapes in carrying the sheets over the plate f, and as it does not quite touch the lower tapes, it does not interfere with or retard the sheets passing under it.

The rock-shaft g is provided with fingers g', which are made to fit against the plate f, to hold the rear edge of the advance sheet until the following sheet has caught up with it, and at this point to release the detained sheet and 90 allow the two to move on together. The shaft is rocked by the arm h and rod i, connecting it with the lever l. The spring j is arranged with reference to the stop k, to hold the fingers g' down while they are moved away by 95 the action of the lever l and wheel F. This arrangement of course can readily be reversed, or so arranged that the lever l will hold them down and the spring move them away or open them.

In order to prevent the tapes from getting out of position, or getting down so as to let the sheets come in contact with the folding-rollers B, I have placed beneath them a cross rod or roller, *q*, which holds them up and in position. Near this supporting-roller is the starting-roller *s*, which has its bearing in a V-shaped lever, *r*. This starting-roller obtains its motion from the tapes, and is so pivoted 10 and operated that a portion of the time it is out of contact with the tapes, it being lowered by the wheel *F* acting on the lever *n*, and raised by the spring *p* acting upon the rod *o*. This operation is so timed that the roller *s* is 15 out of contact with the tapes until the second sheet has caught up with the first, when it is lowered and the fingers *g'* raised, and sufficient tape-pressure is thereby given to put the sheet under motion. As shown, the divider 20 is operated from the opposite side of the machine. The wheel *E* and pivoted lever *t* give the rod *u* a movement in one direction, while the spring *v* moves it in the opposite direction, the rod *u* being connected with the arm *w*, as shown in Fig. 2. This arrangement has 25 been found by actual operation to be very efficient in cumulating two sheets preparatory to presenting them to the folder. Where more than two sheets are to be cumulated, the arrangement shown in my previous application 30 will be adopted, as the arrangement here shown is not adapted to cumulate more than two sheets.

In reference to Fig. 1 it will be observed 35 that the upper or return portion of the tapes *a* and the roller *K* are not shown.

Power to operate the described device may be applied to either end of the shaft *L*, and it is to be taken from the machinery used to 40 drive the folding-rollers, or from the machinery of the printing-press, by suitably connecting them with shafts and gearing in any well known or suitable manner.

What I claim as new, and desire to secure by Letters Patent, is as follows:

45

1. The combination of the tapes *a* and *b*, means, substantially as described, for dividing two sheets advancing between the tapes, a plate, *f*, arranged between the tapes, and vibrating fingers *g'*, arranged above the plate to 50 catch the rear edge of the upper sheet and detain it until the under sheet passes thereunder, as and for the purpose set forth.

2. The combination of the divider *c d*, roller *e*, plate *f*, and detaining-fingers *g'* with the 55 tapes *a b* and roller *s*, substantially as and for the purpose described.

3. The combination, with tapes *a* and *b*, of means, substantially as described, for dividing two sheets entering between the tapes, the 60 plate *f*, arranged between the tapes, vibrating fingers *g'*, arranged above the plate for catching the rear edge of one sheet and detaining it until the succeeding sheet passes under it, the rock-shaft *g*, to which the fingers are attached, the arm *h* on the shaft, the rod *i*, the spring *j*, the lever *l*, and cam-disk *F*, essentially as and for the purpose set forth.

4. The combination, with the tapes *a* and *b* and divider *c d*, of the roller *e*, plate *f*, detaining-fingers *g'*, rock-shaft *g*, arm *h*, rod *i*, spring *j*, lever *l*, and cam-wheel *F*, arranged for operation substantially as and for the purposes described.

5. The combination of the divider *c d*, roller 75 *e*, plate *f*, detaining-fingers *g'*, and roller *s* with the tapes *a b* and folding-rollers *B*, substantially as and for the purpose specified.

6. The combination of the divider *c d* and roller *e* with the tapes *a b*, plate *f*, and the detaining-fingers *g'*, substantially as described.

CONRAD KAHLER.
